CORE AND SHELL FOR ELECTROMOTORS

Ludwig Adam and Rudolf Haackel, Homburg, Saar Territory, and August Schanz, Frankenthal, Pfalz, Germany, assignors to Kleinschanzlin-Pumpen Aktiengesellschaft, Homburg, Saar Territory

Application January 19, 1953, Serial No. 331,962

Claims priority, application Germany January 21, 1952

3 Claims. (Cl. 310—64)

This invention relates to electromotors and more especially to the stator shells which surround the laminated cores or metal plate packs of certain electromotors.

It is an object of this invention to provide sheet metal shells held in place on the metal plate packs by mere friction, created when pressing these shells around the plates and into longitudinal grooves provided in the circumferential surface of the packs and into grooved collars seated on the free ends of the plate pack.

In order to provide for an efficient heat flow also in high-duty electromotors, we fix on the shell proper an additional corrugated sheet metal sleeve which is held in close heat-conductive contact with the shell and provides a large surface for the heat flow. We prefer to solder or weld the corrugated jacket to the shell.

In order to facilitate the pulling down of the shell onto the stator plates, we prefer to use a corrugated sheet metal sleeve which is discontinuous in the vicinity of the longitudinal grooves.

The sleeve may also consist of narrow sheet metal strips containing only one or two corrugations.

The form of the corrugations should be so chosen as to provide for a certain elasticity when drawing the shell onto the plates, and the strips may also be formed with longitudinal ribs formed of a plurality of stiffening beads with contacting inner surfaces.

In the drawings affixed to this specification and forming part thereof several embodiments of our invention are illustrated diagrammatically by way of example.

In the drawings:

Fig. 1 is a plan view of an embodiment showing a corrugated sheet metal sleeve in two parts fastened on the outer surface of the shell.

Figs. 2 and 3 are similar views of two more embodiments.

Referring to the drawings and first to Figs. 1 and 2, 1 is the stator proper consisting of superposed sheet metal laminae. 2 is one of a pair of longitudinal grooves formed in the free faces of the laminae. 3 is the cylindrical steel shell surrounding the pack of laminae, which by pressure has been forced into these grooves as shown at 20.

The sheet metal shell 3, before being placed around the pack 1, has an inner diameter slightly larger than the outer diameter of the pack and can easily be placed around the pack, to be then forced by circumferential pressure into close contact with the pack and held in place on the pack by the part protruding into the groove 2. The shell thus secures the laminae against distortion.

In the embodiment shown in Fig. 1 two corrugated heat abducting sheets are fixed on the outer surface of the shell 3 by soldering or welding, leaving free only the grooved parts of the shell. 2 is one of the longitudinal

2

grooves provided in the circumferential surface of the pack.

According to Fig. 2 a similar heat-abducting system is formed by a number of separate corrugated strips 11, 12, 5 13.

The embodiment of Fig. 3 shows an outer sleeve formed with ribs 14.

In all cases the sheet metal pack forming the body of the stator is placed on a mandrel (not shown) and subjected to a preliminary pressure. On the pack, on which at least two diametrically opposite longitudinal grooves 2 have been formed, a seamless or end-welded sheet metal cylinder 3 is placed, the circumferential pressure acting on the outer surface of the cylinder forces it into close contact with the pack of laminae and also into the longitudinal grooves formed in them.

We wish it to be understood that we do not desire to be limited to the details disclosed in the foregoing specification and illustrated in the drawings for obvious modifications will occur to a person skilled in the art.

We claim:

1. Core and shell for electromotors comprising in combination, an axially grooved laminated sheet metal core presenting a cylindrical outer surface, two axially extending grooves in said surface, a cylindrical sheet metal shell closely surrounding said core, parts of said shell swaged into the grooves of said core to secure tightly said shell to the core, and a plurality of corrugated sheet metal strips fixed to the outer surface of the shell and circumferentially spaced from each other by at least one of said grooves.

2. Core and shell for electromotors comprising in combination, an axially grooved laminated sheet metal core presenting a cylindrical outer surface, two axially extending grooves in said surface, a cylindrical sheet metal shell closely surrounding said core, parts of said shell swaged into the grooves of said core to secure tightly said shell to the core, and two corrugated sheet metal strips fixed to the outer surface of the shell and circumferentially spaced from each other by said two grooves.

3. Core and shell for electromotors comprising in combination, an axially grooved laminated sheet metal core presenting a cylindrical outer surface, two axially extending grooves in said surface, a cylindrical sheet metal shell closely surrounding said core, parts of said shell swaged into the grooves of said core to secure tightly said shell to the core, and a plurality of sheet metal strips fixed to the outer surface of the shell and circumferentially spaced from each other by at least one of said grooves, said sheet metal strips being corrugated to form double-walled ribs.
